UNITED STATES PATENT OFFICE

LEOPOLD RUZICKA, OF DE BILT, NEAR Utrecht, NETHERLANDS, ASSIGNOR TO SOCIÉTÉ ANONYME M. NAEF & CO., OF GENEVA, SWITZERLAND, A CORPORATION OF SWITZERLAND

PROCESS FOR THE PREPARATION OF THE MONOCYCLIC LACTONES HAVING FOURTEEN TO EIGHTEEN RING MEMBERS

No Drawing. Application filed July 16, 1928, Serial No. 293,310, and in Switzerland July 27, 1927.

Closed chain lactones having more than seven ring members have not hitherto been obtainable in the pure state. M. Kerschbaum has however stated in the "Berichte der deutschen Chemischen Gesellschaft", 1927, volume 60, pages 902 and following, that in native substances a lactone is present having 16 and 17 ring members. It is also stated in the specification of German patent application H. 105,677, Class 12 o, published the 25th May 1927, that synthetic lactones are produced having 16 and 17 ring members, which are formed by heating with silver oxide of brominated fatty acids in which the atom of bromine and the carboxyl group are at the opposite ends of the chain. All these lactones are described as being liquids which do not possess clearly defined boiling points; the yields of these products in the synthetic process are so small, that a preparation of the products in the pure state has apparently until now not been possible.

I have however found that it is possible to obtain such lactones in the chemically pure state and in a considerable yield by heating carbocyclic ketones having a large number of ring members such as those described in the United States Patent 1,673,093 and the United States patent applications Serial No. 30 149,534 to No. 149,544 now Patents Nos. 1,702,842 to 1,702,852 respectively, all issued February 19, 1929, with monopersulphuric acid at a temperature of about 30 to 60 degrees centigrade.

35 I thus did obtain from cyclotridecanone the lactone of 12-oxy-dodecane-1-carboxylic acid; from cyclotetradecanone the lactone of 13-oxy-tridecane-1-carboxylic acid; from cyclo-pentadecanone (exaltone) the lactone of 14-oxy-tetradecane-1-carboxylic acid (exaltolid); from cyclo-hexadecanone the lactone of 15-oxy-pentadecane-1-carboxylic acid and from cyclo-heptadecanone (dihydro-zibetone) the lactone of 16-oxy-hexadecan-1-carboxylic acid. All these lactones are solid at a temperature above 25 degrees centigrade and possess clearly defined boiling points.

40 In a similar manner the corresponding lactones can be obtained from alkylated ketones described in the U. S. Patents 1,673,093,

1,702,842 to 1,702,852 inclusively; for instance, from 2-methyl-cyclopenta-decane-1-one (1-methyl-exaltone) a mixture of lactones of the 14-oxy-14-methyl-tetradecane-1-carboxylic acid and the 14-oxy-1-methyl-tetradecane-1-carboxylic acid and from 3-methyl-cyclopentadecane-1-one (muscone) a mixture of lactones of the 14-oxy-13-methyl-tetradecane-1-carboxylic acid and 14-oxy-2-methyl-tetradecane-1-carboxylic acid.

45 It was however already known to be possible to obtain lactones having respectively 7 or 8 ring members by treating ketones having 6 or 7 ring members with monopersulphuric acid, as per Baeyer & Villiger, "Berichte der deutschen Chemischen Gesellschaft", 1899, volume 32, page 3625 and 1900, volume 33, page 862. There appeared however that only such ketones give a good yield of lactones, which possess beside the ketone group substituents such as the isopropyl group and the methyl group. However, ketones which 50 besides the keto-group do not possess any substituent did give either no lactone at all or only a small amount thereof. But then one has to work below 20 degrees centigrade, as at a higher temperature only the splitting product of the lactone, the oxy-acid, is formed. It could therefore not be expected that ketones having a larger number of ring members might give at a higher temperature a yield of more than 50 per cent of pure lactone, even if they possess lateral chains approaching the keto-group. The stability of 55 these lactones against warm monopersulphuric acid is so much more remarkable as a small stability of the same against hydrolyzing agents would rather be expected from the known facility to form lactones having more than seven ring members.

60 When on the contrary, the monopersulphuric acid is allowed to act upon the higher membered ketones under the conditions indicated by v. Baeyer & Villiger, there is obtained only a small quantity of the lactone, and in its place the peroxide of the ketone is formed. When my working conditions are maintained the production of these peroxides is 65 avoided.

The constitution of the prepared unmethylated lactones was proved by splitting the same by means of boiling potash lye to the corresponding oxyacids which when oxidized with chromic acid are transformed into dicarboxylic acids having the same number of carbon atoms.

The herein described lactones have an odor resembling that of musk, civet or that of amber and may be employed in place of such perfumes or as raw materials for the preparation of similar products.

The preparation of lactones having 14 to 18 ring members represents in itself an important technical progress, as it is very important for the use of a substance as a perfume to remove from the same any impurities which may influence the odor thereof.

Example 1

27 grams cyclo-pentadecanone (exaltone) are dissolved in 45 gr. petroleum benzine and added with a filtered solution of 160 gr. persulphate of potassium in 400 gr. concentrated sulphuric acid and 74 gr. water, this addition being made so rapidly that the temperature of the mixture remains about 50 degrees centigrade. A too great rise of temperature may be avoided by an exterior cooling with ice. After standing during several hours the mixture is poured on ice and the layer of benzine is separated. By shaking the mixture with a solution of soda, acid products are extracted. By treating the neutral portion with a solution of semicarbazide the remaining small quantities of unchanged cyclo-pentadecanone which are contained therein are transformed into the semi-carbazone. The easily soluble lactone of the 14-oxy-tetradecane-1-carboxylic acid may then be extracted by means of petroleum spirit

This lactone boils at 176 degrees centigrade under 15 mm. pressure, solidifies quickly into needles melting at 31 to 32 degrees centigrade and presents the following characteristics:

$$D_4^{33} = 0.9447, n_D^{33} = 1.4669.$$

D_4^{33} means the density measured at a temperature of 33 degrees centigrade and relates to water of 4 degrees centigrade;

n_D^{33} or N_D^{33} means refractive index of the D-line of the spectrum determined at a temperature of 33 degrees centigrade.

Example 2

Cyclo-tridecanone is treated in the manner described in Example 1. After treating the neutral reaction product with a solution of semicarbazide the lactone of 12-oxy-dodecane-1-carboxylic acid is extracted by means of petroleum spirit. It boils at 148 degrees under 15 mm. pressure, melts at 26 to 27 de-

grees centigrade and presents the following characteristics:

$$D_4^{33} = 0.9590; n_D^{33} = 1.4649.$$

Example 3

Cyclo-tetradecanone is treated in the manner described in Example 1. After the treatment of the neutral product of reaction with a solution of semicarbazide the lactone of 13-oxy-tridecane-1-carboxylic acid is extracted by means of petroleum spirit. It boils at 165 degrees centigrade under 15 mm. pressure, melts at 29 to 30 degrees centigrade and presents the following characteristics:

$$D_4^{33} = 0.9528; n_D^{33} = 1.4662.$$

Example 4

Cyclo-hexadecanone is treated in the manner described in Example 1. After the treatment of the neutral product of reaction with a solution of semicarbazide the lactone of 15-oxy-pentadecane-1-carboxylic acid is extracted by means of petroleum spirit. It boils at 188 degrees centigrade under 15 mm. pressure, melts at 35 to 36 degrees centigrade and presents the following characteristics:

$$D_4^{33} = 0.9396.$$

Example 5

Cyclo-heptadecanone (dihydro-zibetone) is treated in the manner described in Example 1. After the treatment of the neutral reaction product with a solution of semicarbazide the lactone of 16-oxy-hexadecane-1-carboxylic acid is extracted by means of petroleum spirit; it boils at 194 degrees centigrade under 15 mm. pressure, melts at 41 to 42 degrees centigrade and presents the following characteristics:

$$D_4^{33} = 0.9326; n_D^{33} = 1.4669.$$

Example 6

2-methyl-cyclopentadecane-1-on (Methyl-exaltone) is treated as described in Example 1. After the treatment of the neutral reaction product with a solution of semicarbazide the mixture of the lactones of the 14-oxy-14-methyl-tetradecane-1-carboxylic acid and the 14-oxy-1-methyl-tetradecane-1-carboxylic acid is extracted by means of petroleum spirit; The mixture of lactones boils at 178 degrees centigrade at 15 mm. pressure and presents the following characteristics:

$$D_4^{33} = 0.9301; n_D^{33} = 1.4611.$$

Example 7

3-methyl-cyclopentadecane-1-on (muscone) is treated in the manner described in Example 1. After the treatment of the neutral reaction product with a solution of semicarbazide the mixture of the lactones

of the 14-oxy-13-methyl-tetradecane-1-carboxylic acid and 14-oxy-2 methyl-tetradecane-1-carboxylic acid is extracted by means of petroleum spirit. The mixture of lactones boils at 180 degrees centigrade at 15 mm. pressure and presents the following characteristics:

$$D_4^{33} = 0.9305; n_D^{33} = 1.4614.$$

10 With respect to the number of ring members mentioned in the claims 1 and 2 the following explanation is given:

By "14 to 18 ring members" applicant means that besides the 13 to 17 carbon atoms there is furthermore one oxygen atom which by the conversion of the ketones into the lactones is inserted as ring member. That means in a general manner:

20 The lactone obtained from a ketone possesses one ring member more than the ketone, this ring member being an oxygen atom according to the following formula:

What I claim is:

1. A process for the preparation of the monocyclic lactones having 14 to 18 ring members, consisting in heating monocyclic 30 ketones having 13 to 17 ring members with persulphuric acid.

2. A process for the preparation of the monocyclic lactones having 14 to 18 ring members, consisting in heating monocyclic 35 ketones having 13 to 17 ring members with persulphuric acid at a temperature of about 30 to 60 degrees centigrade.

3. A process for the preparation of the lactone from 14-oxy-tetradecane-1-carboxylic 40 acid, consisting in heating cyclo-pentadecanone with persulphuric acid.

4. A process for the preparation of the lactone from 14-oxy-tetradecane-1-carboxylic acid, consisting in dissolving cyclo-pentadecanone in petroleum benzine, adding a solution 45 of persulphate of potassium in sulphuric acid and water, maintaining the temperature at about 50 degrees centigrade, after several hours standing, pouring the mixture on ice, separating the layer of benzine extracting the acid products by means of a solution of soda, treating the neutral reaction product with a solution of semicarbazide, extracting the lactone of 14-oxy-tetradecane-1-

50 carboxylic acid by means of petroleum spirit.

55 5. The lactone from 14-oxy-tetradecane-1-carboxylic acid boiling at 176 degrees centigrade under 15 mm. pressure, solidifying into needles melting at 31-32 degrees centigrade 60 and presenting the following characteristics:

$$D_4^{33} = 0.9447; n_D^{33} = 1.4669.$$

In testimony whereof I affix my signature.
LEOPOLD RUZICKA.
